ATTORNEY

UNITED STATES PATENT OFFICE.

CYRUS F. BLANKE, OF ST. LOUIS, MISSOURI, ASSIGNOR TO ST. LOUIS TIN & SHEET METAL WORKING CO., OF ST. LOUIS, MISSOURI, A CORPORATION OF MISSOURI.

SUITCASE.

1,299,291.

Specification of Letters Patent.

Patented Apr. 1, 1919.

Application filed December 7, 1917. Serial No. 205,967.

To all whom it may concern:

Be it known that I, CYRUS F. BLANKE, a citizen of the United States, residing at St. Louis, State of Missouri, have invented a new and useful Suitcase, of which the following is a specification.

The invention relates to a case, and more particularly to the class of metallic suit cases.

10 The primary object of the invention is the provision of a case of this character in which the body thereof is made from sheet material, preferably metal, in a plurality of sections, which are united in a unique manner to insure strength and rigidity to the body as a unit, and, at the same time avoid the use of corner clips or other reinforcements thereby enabling the case to be constructed and assembled at a minimum expense, and reducing the cost of manufacture.

Another object of the invention is the provision of a case of this character, which is light in weight, neat and attractive in appearance, and useful as a sample or traveling case, although the same may be used for any other purpose.

With these and other objects in view, the invention consists in the features of construction, combination and arrangement of parts, as will be hereinafter fully described, illustrated in the accompanying drawing, and pointed out in the claim hereunto appended.

35 In the accompanying drawing—

Figure 1 is a perspective view of the case constructed in accordance with the invention, closed.

Fig. 2 is a vertical, longitudinal sectional view.

40 Fig. 3 is a vertical transverse sectional view.

Fig. 4 is a fragmentary sectional view on the line 4—4 of Fig. 2, looking in the direction of the arrow.

45 Fig. 5 is a perspective view of the case open, with the side or bottom removed.

Fig. 6 is a perspective view of the side or bottom removed.

Similar reference characters indicate corresponding parts throughout the several views of the drawing.

Referring to the drawing in detail, A designates generally the body, and B the swinging top or cover section of the case, which is preferably made from sheet metal,

although the same can be made from any other suitable material.

The body A comprises a substantially rectangular-shaped frame, formed from a strip bent to provide the walls 9, 10 and 11, respectively, of said body, while the wall 12 opposite the wall 10 is formed from a separate strip which is of less length than said wall, the meeting ends of the two strips being united by overlapping interlocked 60 joints or seams 13, which securely fasten and hold the strips together, without the use of rivets or other like fasteners.

The side 14, which constitutes the bottom of the body A, is formed from a single section, stamped or cast by the use of a die or other form to provide a marginal unbroken flange 15, the free edge of which is rolled or outwardly and inwardly curled to form a reinforcing bead 16 which is offset from 70 the flange, and this marginal flange 15 embraces the frame exteriorly of all of its walls to close one side of said frame. By reason of the offset disposition of the bead the marginal edge of the body fits flat against the 80 inner side of the flange.

At intervals throughout the extent of the marginal flange 15, are rivets 17, which are passed therethrough, and also through the frame for securing the side 14 thereto. 85

The other side 18 of the case constitutes the swinging top or cover section for the case, and is made from a single section, stamped or cast in a manner identical with the formation of the side 14, to provide a marginal unbroken flange 19, having the outwardly offset reinforcing bead 20, which is coextensive with the flange except at the points of location of the hinges 21, which are riveted or otherwise fastened to the wall 95 12 near the seams 13, for swingingly connecting the top or cover section to the frame. The bead 20 is formed by outwardly and inwardly curving the free edge of the flange 19, thereby reinforcing the side 18, and this flange 19 embraces the frame when the top or cover section is closed. The outward disposition of the bead 20 on the cover section has the same purpose as the offset arrangement of the bead 16 of the bottom section. 100 105

Mounted on the frame upon the wall 10, is the usual handle 22, for the convenient carriage of the suitcase when in use, while on opposite sides of this handle and fixed to the frame and the top or cover section 18, 110

are the parts 23 and 24, respectively, of clamps for fastening the top or cover section closed, the clamps being of the ordinary well known construction.

5 It will be noted that the suit case is formed of four separate pieces, excluding the handle, the locking connections and hinges, the body being made of three pieces, and the cover of a single piece. By this
10 construction, the corners of the suit case are left unbroken, with the result that metal reinforcements are made unnecessary, the beads at 16 and 20 not only imparting to the suit case an ornamental appearance, but also
15 strengthening the same.

From the foregoing, it is thought that the construction of the case will be clearly understood, and therefore a more extended explanation has been omitted. However,
20 changes, variations and modifications may be made in the case, such as come properly within the scope of the appended claim, without departing from the spirit of the invention, or sacrificing any of its advantages.

25 What is claimed is:—
In a suit case, the combination with a

rectangular body frame formed of sheet metal with four unbroken corners or angles, said body frame having one wall formed of a separate strip of less length than said 30 wall and joined by seams to the remaining portion of said frame, of two sides forming the top and bottom of the case, each side being stamped from sheet metal to provide a marginal flange with solid corners, with 35 an outwardly offset bead at the free edge of said flange, the said body having its free edges fitting within the flanges of said sides and bearing flat against the inner faces of said flanges, rivets securing the free edge 40 of the body to the flange of the side forming the bottom below the bead thereof, and hinges connecting the flange of the side forming the top to the separate strip of the body contiguous to said seams.

45 In testimony, that I claim the foregoing as my own, I have hereto affixed my signature in the presence of two witnesses.

CYRUS F. BLANKE.
